UNITED STATES PATENT OFFICE.

THOMAS F. BRAZIL, OF NEW BEDFORD, MASSACHUSETTS, ASSIGNOR TO DRAPER CORPORATION, OF HOPEDALE, MASSACHUSETTS, A CORPORATION OF MAINE.

SHUTTLE FOR SIDE-MOTION FEELER-LOOMS.

1,202,629.

Specification of Letters Patent. Patented May 6, 1919.

Application filed September 16, 1918. Serial No. 254,230.

To all whom it may concern:

Be it known that I, THOMAS F. BRAZIL, a citizen of the United States, residing at New Bedford, county of Bristol, State of Massachusetts, have invented an Improvement in Shuttles for Side-Motion Feeler-Looms, of which the following description, in connection with the accompanying drawing, is a specification, like characters on the drawing 10 representing like parts.

This invention relates to the construction of shuttles for use in side motion feeler looms. In such type of looms, as is well known to those skilled in the art, a feeler is employed 15 which upon the beat up of the lay enters the shuttle recess and contacts with the mass of filling upon the filling carrier. The feeler mechanism is so constructed that, when the running filling has reached a predetermined degree of exhaustion or has become 20 entirely exhausted, the feeler has a side motion, usually due to it, or some portion of it, slipping on the smooth surface of the filling carrier, and this side motion is utilized 25 to effect the initiation of filling replenishment or other change in the operation of the loom.

The object of this invention is to provide a shuttle having means for preventing a premature side motion of the feeler taking place 30 and consequently a premature replenishment of the shuttle with a fresh filling carrier or other premature change in the operation of the loom. The danger of such premature action, which this invention prevents, arises chiefly from the not infrequent mis-positioning of the shuttle longitudinally at the time the feeling action occurs. This mis-positioning of the shuttle is due to a 40 slight rebound or a failure fully to enter the shuttle box at the feeling end of the loom and in either case results in bringing the path of feeler movement nearer the butt end of the shuttle recess than the normal 45 path of feeler movement. This brings the feeler opposite the smooth outer wall of the shuttle or, if the slot into the shuttle recess be extended, opposite the smooth surface of the means employed for clamping and holding the butt of the filling carrier such as the usual bifurcated metal clamping guide. Consequently, when the beat up occurs, the feeler engages a smooth surface and side motion takes place in the same

manner as if it had engaged a depleted bobbin barrel.

In the preferred form of the invention the desired object is secured by extending the usual feeler slot in the shuttle wall toward the butt end of the shuttle recess so as 60 to expose the means, such as the usual metal clamping guide, for holding the butt of the filling carrier, and by providing the surface thus exposed with serrations which term includes any form of roughness sufficient to 65 prevent side motion of the feeler when the feeler is in contact therewith. But the invention in its broader aspect is not to be limited to this preferred form nor otherwise than by the appended claims, because I believe I am the first so to construct the shuttle itself that premature actuating side motion of a side motion feeler, due to longitudinal mis-positioning of the shuttle at the time of feeling, is prevented.

The nature and object of the invention will appear more fully from the accompanying description and drawing and will be particularly pointed out in the appended claims.

In the drawings which represent the preferred form of the invention,

Figure 1 is a side elevation of the end of a shuttle;

Fig. 2 is a top plan view of the shuttle 85 with the butt and a portion of the barrel of a filling carrier indicated in dotted lines;

Fig. 3 is a perspective view of a bifurcated clamping guide provided with the external serrated surface.

From the statement already made it will be apparent that the construction and operation of the loom and of a side motion feeler mechanism is unchanged by this invention which has to do only with the construction 95 of the shuttle itself. Consequently this description is restricted to the shuttle.

In its general construction the shuttle may be of any usual type. In the preferred form illustrated the body of the shuttle is provided with the usual recess 1 extending through the shuttle from top to bottom to receive the filling carrier which, as indicated in dotted lines, may be a wooden bobbin 2 of usual type. Such a filling carrier 100 is commonly clamped and held in the shuttle recess 1 by a bifurcated metal clamping guide shown, together with the novel ser-

rated surface, separately in Fig. 3. The shank 3 of this clamping guide is rigidly secured in the body of the shuttle with the arms 4 and 5 projecting into the recess 1 substantially parallel to the side walls 6 and 7 thereof. The inner surfaces of these arms are usually grooved at 8 to coöperate with rings 9 on the butt of the filling carrier in accurately positioning and firmly holding 10 the filling carrier.

The side wall 7 is slotted longitudinally at 10 opposite the axis of the filling carrier to enable the feeler to enter the recess 1 and feel the filling on the filling carrier. 15 In the case of a side motion feeler mechanism, with which the shuttle of this invention is to coöperate, the feeler entering the slot 10 upon the beat up contacts with the filling carrier; if the required amount of 20 filling is present side motion of the feeler is absent, but, if the filling has become exhausted or has reached a predetermined degree of exhaustion, then the feeler contacting with the relatively smooth and hard 25 surface of the filling carrier undergoes some sort of side motion depending upon the character of the specific feeler mechanism employed and this side motion is utilized through a suitable train of mechanism to 30 initiate filling replenishment or other change in the operation of the loom.

But, as already pointed out, longitudinal mis-positioning of the shuttle at the time of feeling, due to rebound or improper boxing 35 of the shuttle or other cause, will so relate the shuttle to the path of feeler movement that the feeler will not be opposite the filling on the filling carrier but will be in a position opposite a point nearer the butt 40 of the filling carrier or the butt end of the shuttle recess. Under such conditions, when the beat up occurs, the feeler contacts with a smooth hard surface which has no relation to the condition of the filling on the 45 filling carrier and consequently side motion may take place resulting in premature initiating action of the feeler mechanism.

This result is obviated in the preferred form of the invention illustrated by extending 50 the slot 10 in the shuttle wall toward the butt end of the recess 1 sufficiently to expose the arm 5 of the bifurcated clamping guide and by serrating as at 11 the external exposed face of this arm 5. It is found 55 in practice that such an extension of the slot 10 for the length of the usual arm 5 is sufficient to cover the range of shuttle mis-positioning for which it is necessary to provide the surface of the arm 5 is shown 60 as serrated by vertical ridges but any form of roughness sufficient to prevent side mo-

tion of a feeler in contact therewith is to be included as a serrated surface.

Thus it will be seen that if the shuttle be longitudinally mis-positioned when feeling takes place this invention provides means which prevents premature side motion of the feeler with its consequent premature initiation of filling replenishment or other change in the operation of the loom.

Having fully described my invention, what I claim as new and desire to secure by Letters Patent is:

1. A shuttle for use in side motion feeler looms provided with a filling carrier recess and with means to clamp and hold a filling carrier by its butt in said recess, one wall of said recess being slotted to permit the passage of the feeler therethrough, the said shuttle being further provided with an external serrated surface located in alignment longitudinally of the shuttle with, but nearer the butt end of the shuttle recess than, the normal path of the feeler movement, whereby, if the shuttle be longitudinally mis-positioned at the time of feeling, premature actuation of the feeler will be prevented by its engagement with said serrated surface.

2. A shuttle for use in side motion feeler looms having the construction defined in claim 1 in which the said serrated surface is located upon the means to clamp and hold the filling carrier by its butt.

3. A shuttle for use in side motion feeler looms provided with a filling carrier recess and with a bifurcated metal clamping guide in said recess to clamp and hold a filling carrier by its butt, one wall of said recess being slotted to permit the passage of the feeler therethrough, the said slot being extended toward the butt end of the shuttle recess and opposite said clamping guide, and the said clamping guide having its external face exposed by said extended slot serrated, whereby, if the shuttle be longitudinally mis-positioned at the time of feeling, premature actuation of the feeler will be prevented by its engagement with said serrated surface.

4. A shuttle for use in side motion feeler looms comprising a body having a filling carrier recess and a slot through the wall of said recess to permit the passage of the feeler, and comprising means carried by the shuttle and acting when the shuttle is longitudinally mis-positioned at the time of feeling to engage the feeler and prevent premature side motion of the feeler.

In testimony whereof I have signed my name to this specification.

THOMAS F. BRAZEIL.
